ABSTRACT

The vessel azimuth control apparatus has an azimuth control unit that outputs a steering-angle command signal for making a vessel turn to an azimuth to which the vessel should travel, based on an azimuth command signal generated by an azimuth command generation unit, a yaw-angle signal, and a yaw-angular-velocity signal,

a steering-angle control unit that controls a rudder based on the steering-angle command signal, and

a control gain adjustment unit that has a calculation feasibility determination unit for determining feasibility of calculation of frequency responses, based on the yaw-angle signal and the yaw-angular-velocity signal, and that calculates respective frequency responses of the yaw-angle signal and the yaw-angular-velocity signal for the steering-angle signal, when the calculation feasibility determination unit determines that calculation of frequency response are feasible, and then adjusts a control gain of the azimuth control unit.

VESSEL AZIMUTH CONTROL APPARATUS AND AZIMUTH CONTROL METHOD

TECHNICAL FIELD

The present disclosure relates to a vessel azimuth control apparatus and an azimuth control method.

BACKGROUND

There exists an azimuth control apparatus that performs steering in such a way as to orient the traveling direction of a vessel to a designated course and to maintain the traveling direction. A vessel azimuth control apparatus is referred to also as a vessel automatic steering apparatus or an autopilot. A vessel azimuth control apparatus controls a rudder in such a way as to make a yaw angle, which is a rotation angle around the vertical-direction axis that passes through the gravity center of a vessel, coincide with a designated azimuth.

A vessel azimuth control apparatus is an apparatus that controls a rudder in order to make a bow azimuth (yaw angle) follow a designated azimuth. A vessel azimuth control apparatus multiplies the difference between a designated azimuth and a bow azimuth by a predetermined control gain so as to generate a steering-angle command and controls a rudder in accordance with the steering-angle command. A vessel azimuth control apparatus drives a rudder through a rudder driving unit. The rudder driving unit drives the rudder and makes the vessel induce a yaw rate so as to change the bow azimuth.

In a vessel azimuth control apparatus, it is required to optimize the control gain in order to prevent disturbance factors, such as a tidal current, an ocean wave, and a storm, from promoting vibration of the vessel. The control gain can be determined based on vessel parameters. However, vessel parameters change in accordance with a change in a vessel speed, a draft, or the like.

Accordingly, it is required to cope with a change in the vessel parameters. An actual vessel is made to sail, and then input data pieces (steering angles) and output data pieces (bow azimuths) are accumulated. In contrast to the accumulated data pieces, input data pieces (steering angles) are provided to a vessel model formed by preliminarily and tentatively determining the vessel parameters, so that output data pieces (bow azimuths) are calculated. There has been disclosed a technology (e.g., Patent Document 1) in which based on the result of comparison between the calculated bow azimuth and an actually measured bow azimuth, the vessel parameters are adjusted (modified).

CITATION LIST

Patent Literature

Patent Document 1: Japanese Patent Application Laid-Open No. 2006-321455

However, in the vessel azimuth control apparatus disclosed in Patent Document 1, a steering-angle offset and vessel parameters for expressing a disturbance model such as a tidal current are regarded as fixed values. The steering-angle offset signifies a counter-steering amount required when a vessel travels straight ahead. By accumulating steering-angle commands and bow-azimuth data pieces and by utilizing SQP (Sequential Quadratic Programming) algorithm, the steering-angle offset and the vessel parameters are identified. When the steering-angle offset is regarded as a

fixed value, it is not made possible to consider the effects of a change in the vessel azimuth and the disturbance that changes from moment to moment.

As a result, in the case where a steering-angle command to be utilized in identification requires a large veering change in the bow-azimuth data, the vessel parameters cannot adequately be identified, due to the restriction caused by regarding the steering-angle offset as a fixed value. When the vessel parameters are inadequate values, the control gain to be determined based on the vessel parameters becomes an inadequate value. This poses a problem that an unintended azimuth-control response is made.

In addition, in the vessel azimuth control apparatus disclosed in Patent Document 1, a step-like veering change is provided to the vessel azimuth command value and then the steering-angle offset and the vessel parameters are identified by use of the steering-angle command and the bow-azimuth data at that time. Accordingly, there exists a problem that for an arbitrary-pattern steering during normal sailing, identification of the steering-angle offset and the vessel parameters cannot be executed.

Moreover, in Patent Document 1, with regard to the vessel azimuth control apparatus, there exists a description that satisfactory identification has been performed by a single step-like veering action. It is described that there has been calculated a control gain based on which satisfactory veering characteristics are obtained. However, the number of necessary veering actions and the veering pattern change depending on the vessel shape, the load amount, the vessel speed, and the veering amount. Patent Document 1 does not clarify any quantitative guiding principle such as which pattern of veering action makes it possible to calculate satisfactory control gain.

SUMMARY

The present disclosure has been implemented in order to solve the foregoing problems. The objective thereof is to obtain an azimuth control apparatus and an azimuth control method that can calculate, during sailing, vessel parameters for calculating an adequate control gain for an arbitrary steering pattern at a time of sailing, while considering a change in the sailing azimuth and the effect of disturbance that changes from moment to moment.

The foregoing and other object, features, aspects, and advantages of the present invention will become more apparent from the following detailed description of the present invention when taken in conjunction with the accompanying drawings.

Solution to Problem

A vessel azimuth control apparatus according to the present disclosure includes

an azimuth command generation unit that generates an azimuth command signal indicating an azimuth to which a vessel should travel,

a yaw-angle detection unit that outputs a yaw-angle signal indicating a rotation angle around a vertical axis passing through the gravity center of the vessel,

a yaw-angular-velocity detection unit that outputs a yaw-angular-velocity signal indicating a rotation angular velocity around the vertical axis passing through the gravity center of the vessel,

a steering-angle detection unit that outputs a steering-angle signal indicating an angle of a rudder of the vessel,

a vessel-speed detection unit that outputs a vessel-speed signal indicating a speed of the vessel, an azimuth control unit that outputs a steering-angle command signal for making the vessel turn to the azimuth to which the vessel should travel, based on the azimuth command signal generated by the azimuth command generation unit, the yaw-angle signal outputted by the yaw-angle detection unit, and the yaw-angular-velocity signal outputted by the yaw-angular-velocity detection unit, a steering-angle control unit that controls a rudder, based on the steering-angle command signal outputted by the azimuth control unit, and a control gain adjustment unit that has a calculation feasibility determination unit for determining feasibility of calculation of frequency responses, based on the steering-angle signal, yaw-angle signal and the yaw-angular-velocity signal, and that calculates respective frequency responses of the yaw-angle signal and the yaw-angular-velocity signal for the steering-angle signal outputted by the steering-angle detection unit, when the calculation feasibility determination unit determines that calculation of frequency responses are feasible, and then adjusts a control gain of the azimuth control unit.

A vessel azimuth control method according to the present disclosure includes

a step in which an azimuth command generation unit generates an azimuth command signal indicating an azimuth to which a vessel should travel, a step in which a yaw-angle detection unit outputs a yaw-angle signal indicating a rotation angle around a vertical axis passing through a gravity center of the vessel, a step in which a yaw-angular-velocity detection unit outputs a yaw-angular-velocity signal indicating a rotation angular velocity around the vertical axis passing through the gravity center of the vessel, a step in which a steering-angle detection unit outputs a steering-angle signal indicating an angle of a rudder of the vessel, a step in which an azimuth control unit outputs a steering-angle command signal for making the vessel turn to the azimuth to which the vessel should travel, based on the azimuth command signal generated by the azimuth command generation unit, the yaw-angle signal outputted by the yaw-angle detection unit, and the yaw-angular-velocity signal outputted by the yaw-angular-velocity detection unit, a step in which a steering-angle control unit controls a rudder, based on the steering-angle command signal, and a step in which a calculation feasibility determination unit provided in a control gain adjustment unit determines feasibility of calculation of frequency responses, based on the steering-angle signal, the yaw-angle signal, and the yaw-angular-velocity signal, and in which, when the calculation feasibility determination unit determines that calculation of frequency responses are feasible, the control gain adjustment unit calculates respective frequency responses of the yaw-angle signal and the yaw-angular-velocity signal for the steering-angle signal and then adjusts a control gain of the azimuth control unit.

Advantageous Effects

The present disclosure makes it possible to obtain an azimuth control apparatus and an azimuth control method

that can calculate, during sailing, vessel parameters for calculating an adequate control gain for an arbitrary steering pattern at a time of sailing, while considering a change in the sailing azimuth and the effect of disturbance that changes from moment to moment.

BRIEF DESCRIPTION OF DRAWINGS

FIG. 1 is a configuration diagram of an azimuth control apparatus according to Embodiment 1;

FIG. 2 is a hardware configuration diagram of the azimuth control apparatus according to Embodiment 1;

FIG. 3 is an explanatory chart of a coordinate system of a vessel in which the azimuth control apparatus according to Embodiment 1 is provided;

FIG. 4 is a flowchart representing basic operation of the azimuth control apparatus according to Embodiment 1;

FIG. 5 is a block diagram representing the configuration of an azimuth command generation unit of the azimuth control apparatus according to Embodiment 1;

FIG. 6 is a block diagram representing the configuration of an azimuth control unit of the azimuth control apparatus according to Embodiment 1;

FIG. 7 is a block diagram representing the configuration of a control calculation unit of the azimuth control apparatus according to Embodiment 1;

FIG. 8 is a block diagram representing the configuration of a control gain adjustment unit of the azimuth control apparatus according to Embodiment 1;

FIG. 9 is a chart representing vessel characteristic information of the azimuth control apparatus according to Embodiment 1;

FIG. 10 is a block diagram representing the configuration of frequency responses calculation unit of the azimuth control apparatus according to Embodiment 1;

FIG. 11 is a configuration diagram of an azimuth control apparatus according to Embodiment 2;

FIG. 12 is a block diagram representing the configuration of frequency responses calculation unit of the azimuth control apparatus according to Embodiment 2;

FIG. 13 is a configuration diagram of an azimuth control apparatus according to Embodiment 3; and

FIG. 14 is a block diagram representing the configuration of frequency responses calculation unit of the azimuth control apparatus according to Embodiment 3.

DESCRIPTION OF EMBODIMENTS

Hereinafter, preferred embodiments of a vessel azimuth control apparatus and an azimuth control method will be explained with reference to the drawings. In each of the embodiments, the same or equivalent constituent elements are designated by the same reference characters, and the explanation therefor will be omitted.

1. Embodiment 1

<Configuration of Azimuth Control Apparatus>

FIG. 1 represents a configuration example of a vessel 1 equipped with a vessel azimuth control apparatus 10 according to Embodiment 1. The azimuth control apparatus 10 provided in the vessel 1 receives operation information CI and various kinds of sensor information items from an operational device 30 and a sensor group 20, respectively, and then outputs a steering-angle driving command signal RUAD.

The azimuth control apparatus **10** includes an azimuth command generation unit **100**, an azimuth control unit **200**, a control gain adjustment unit **500** having a gain adjusting unit **300** and frequency responses calculation unit **400**, and a steering-angle control unit **600**. The azimuth control apparatus **10** inputs respective signals of detection units from the sensor group **20** and receives an azimuth command signal DRC, which indicates an azimuth to which the vessel **1** should travel, from the azimuth command generation unit **100**. Then, the azimuth control apparatus **10** outputs a steering-angle driving command signal RUAD to a steering-angle driving unit **40** so as to control the steering angle. The steering-angle driving unit **40** operates the vessel rudder in accordance with the steering-angle driving command signal RUAD. As a result, the azimuth control apparatus **10** makes the azimuth of the vessel **1** changed or held by outputting the azimuth command signal DRC, which indicates an azimuth to which the vessel **1** should travel.

In FIG. 1, the vessel **1** is provided with an unrepresented propulsion unit for propelling a vessel. The output of the propulsion unit is operated through the operational device **30**. As the propulsion unit of the vessel **1**, an outboard engine can be utilized. In an outboard engine, a screw, as a propelling and steering mechanism, is integrally provided under the engine. An outboard engine is a propulsion system whose main body is mounted on the outside of the vessel. Control of a traveling azimuth by an outboard engine is performed by changing the mounting angle of the outboard-engine main body in the vessel. An outboard engine is often adopted in a small boat. It may be allowed that two or more outboard engines are provided.

Application of the azimuth control apparatus **10** according to Embodiment 1 is not limited to the application to a vessel provided with an outboard engine. In many cases, a large ship is provided with an inboard engine. An inboard engine is a propelling and steering mechanism having a form in which a driving unit such as an engine is disposed inside a vessel, in which a screw that is coupled with the driving unit and whose rotation direction is changeable is exposed outside the vessel, and in which the rudder is separated from the screw. The azimuth control apparatus **10** according to Embodiment 1 can be applied also to a vessel provided with a propulsion system based on an inboard engine.

In addition, there exists a vessel provided with an inboard-outdrive engine. An inboard-outdrive engine is a propelling and steering mechanism having a form in which a driving unit such as an engine is disposed inside a vessel and in which a screw that is coupled with the driving unit outside the vessel and whose rotation direction is changeable is integrated with the rudder. The azimuth control apparatus **10** according to Embodiment 1 can be applied also to a vessel provided with an inboard-outdrive engine.

The operational device **30** is utilized also when a vessel operator inputs an initial condition and a terminal condition for sailing of a vessel. The sensor group **20** includes, for example, a Global Navigation Satellite System (hereinafter, referred to as a GNSS for measuring the latitude and the longitude of the vessel **1** and a magnetic azimuth sensor for measuring the azimuth angle of the vessel **1**. It may be allowed that the sensor group **20** is provided with an inertial navigation system connected with a gyroscope for measuring the angular velocity of the vessel **1**, an acceleration sensor for measuring the translational acceleration of the vessel **1**, and the like.

Specifically, as the sensor group **20**, there is provided a yaw-angle detection unit **21** that outputs a yaw-angle signal **Y** indicating a rotation angle around the vertical axis passing

through the gravity center of the vessel **1**. There is provided a yaw-angular-velocity detection unit **22** that outputs a yaw-angular-velocity signal **YR** indicating a rotation angular velocity around the vertical axis passing through the gravity center of the vessel **1**. There is provided a vessel-speed detection unit **23** that outputs a vessel-speed signal **V** indicating a vessel speed of the vessel **1**.

Moreover, there may be provided a steering-angle detection unit **24** that outputs a steering-angle signal **RUA** indicating a steering angle of the vessel **1**. In this situation, although as the yaw-angular-velocity detection unit **22**, a sensor for detecting the angular velocity may independently be provided, the angular velocity may be calculated from a value obtained by time-differentiating the yaw-angle signal **Y**, which is the output of the yaw-angle detection unit **21**. The vessel-speed detection unit **23** may obtain the vessel speed by means of a screw tachometer, a water-surface speed meter, an airspeed meter, an acceleration sensor, a GNSS, a Doppler measurement device based on an electric wave or a laser beam, or the like.

<Functions of Azimuth Control Apparatus>

The azimuth control apparatus **10** has the azimuth command generation unit **100** that generates the azimuth command signal DRC indicating the azimuth to which the vessel should travel. The azimuth control apparatus **10** receives the yaw-angle signal **Y**, the yaw-angular-velocity signal **YR**, the steering-angle signal **RUA**, and the vessel-speed signal **V** from the sensor group **20**. The azimuth control apparatus **10** receives the operation information **CI** from the operational device **30**.

In response to the azimuth command signal DRC generated by the azimuth command generation unit **100**, the azimuth control unit **200** receives the yaw-angle signal **Y**, the yaw-angular-velocity signal **YR**, and the vessel-speed signal **V** and then outputs a steering-angle command signal **RUAC** based on a control gain in which the stability and the responsiveness coexist with each other. The steering-angle control unit **600** receives the steering-angle command signal **RUAC**, generates the steering-angle driving command signal **RUAD**, and then outputs the steering-angle driving command signal **RUAD** to the steering-angle driving unit **40** so as to control the rudder of the vessel **1**.

In response to the operation information **CI** from the operational device **30**, the azimuth control unit **200** outputs an instruction for obtaining the respective frequency responses of the yaw-angle signal **Y** and the yaw-angular-velocity signal **YR** to the steering-angle signal **RUA** for the vessel **1**. Specifically, the azimuth control unit **200** outputs the steering-angle command signal **RUAC** in the shape of a rectangular wave or a saw-tooth wave, and then the control gain adjustment unit **500** obtains output data of each of the yaw-angle signal **Y** and the yaw-angular-velocity signal **YR** to the steering-angle command signal **RUAC**.

The control gain adjustment unit **500** calculates the frequency responses based on the obtained output data, and then adjusts the control gain of the azimuth control unit **200** in accordance with the frequency responses. This adjustment makes it possible that even when the vessel parameters of the vessel **1** change, for example, due to a change in the vessel speed or the draft, the control gain corresponding to this change is acquired. As a result, there can be performed azimuth control in which the stability and the responsiveness coexist with each other.

In the present embodiment, there has been explained the case where the instruction for obtaining the respective frequency responses of the yaw-angle signal **Y** and the yaw-angular-velocity signal **YR** to the steering-angle signal

RUA for the vessel **1** is implemented by means of the operation information CI from the operational device **30**. However, it may be allowed that when detecting that the vessel **1** continues its sailing to the same stable azimuth, the azimuth control unit **200** determines to obtain the frequency responses, as may be necessary, and then outputs the steering-angle command signal RUAC in the shape of a rectangular wave or a saw-tooth wave. For example, it may be allowed that every predetermined time or each time the azimuth control apparatus **10** is started, the azimuth control unit **200** performs frequency-response obtaining operation and the control gain adjustment unit **500** calculates the frequency responses so that the control gain of the azimuth control unit **200** is adjusted.

In addition to this, it is also made possible that in the case where without intermediary of the azimuth control unit **200**, a vessel operator manually outputs the steering-angle command signal RUAC in an arbitrary shape, by use of a steering wheel, a joystick, or the like, and in the case where during normal sailing, the steering-angle command signal RUAC is outputted in response to the azimuth command signal DRC generated based on the operation information CI from the operational device **30**, the control gain is adjusted. It may also be allowed that the control gain of the azimuth control unit **200** is adjusted by outputting, in response to the azimuth command signal DRC, the steering-angle command signal RUAC generated based on the yaw-angle signal Y, the yaw-angular-velocity signal YR, the vessel-speed signal V, and the control gain and then by making the control gain adjustment unit **500** obtain the respective output data pieces on the yaw-angle signal Y and the yaw-angular-velocity signal YR.

<Hardware Configuration of Azimuth Control Apparatus>

FIG. 2 is a hardware configuration diagram of the azimuth control apparatus **10**. The hardware configuration in FIG. 2 can be applied to each of electronic control systems **10a** and **10b**. Hereinafter, as the representative, the azimuth control apparatus **10** will be explained. In the present embodiment, the azimuth control apparatus **10** is an electronic control apparatus that controls the azimuth of a vessel. Respective functions of the azimuth control apparatus **10** are realized by processing circuits provided in the azimuth control apparatus **10**. Specifically, the azimuth control apparatus **10** includes, as the processing circuits, a computing processing unit (computer) **90** such as a CPU (Central Processing Unit), storage apparatuses **91** that exchange data with the computing processing unit **90**, an input circuit **92** that inputs external signals to the computing processing unit **90**, an output circuit **93** that outputs signals from the computing processing unit **90** to the outside, and the like.

It may be allowed that as the computing processing unit **90**, an ASIC (Application Specific Integrated Circuit), an IC (Integrated Circuit), a DSP (Digital Signal Processor), an FPGA (Field Programmable Gate Array), each of various kinds of logic circuits, each of various kinds of signal processing circuits, or the like is provided. In addition, it may be allowed that as the computing processing unit **90**, two or more computing processing units of the same type or different types are provided and respective processing items are executed in a sharing manner. As the storage apparatuses **91**, there are provided a RAM (Random Access Memory) that can read data from and write data in the computing processing unit **90**, a ROM (Read Only Memory) that can read data from the computing processing unit **90**, and the like. As the storage apparatus **91**, a nonvolatile or volatile semiconductor memory such as a flash memory, an EPROM, or an EEPROM, a magnetic disk, a flexible disk, an optical

disk, a compact disk, a minidisk, a DVD, or the like may be utilized. The input circuit **92** is connected with various kinds of sensors including the sensor group **20** and the output signal of the operational device **30**, switches, and communication lines, and is provided with an A/D converter, a communication circuit, and the like for inputting output signals from these sensors and switches and communication information to the computing processing unit **90**. The output circuit **93** is provided with a driving circuit and the like for outputting control signals from the computing processing unit **90** to driving apparatuses including the steering-angle driving unit **40**.

The computing processing unit **90** executes software items (programs) stored in the storage apparatus **91** such as a ROM and collaborates with other hardware devices in the azimuth control apparatus **10**, such as the storage apparatus **91**, the input circuit **92**, and the output circuit **93**, so that the respective functions provided in the azimuth control apparatus **10** are realized. Setting data items such as a threshold value and a determination value to be utilized in the azimuth control apparatus **10** are stored, as part of software items (programs), in the storage apparatus **91** such as a ROM. It may be allowed that the respective functions included in the azimuth control apparatus **10** are configured with either software modules or combinations of software and hardware.

<Coordinate System and Yaw Angle>

FIG. 3 is an explanatory chart of a coordinate system of the vessel **1** in which the azimuth control apparatus **10** according to Embodiment 1 is provided. A coordinate system X1-Y1-Z1 is the one whose reference is a fixed point on the ground that is 0 m above sea level or on the water surface. A coordinate system X0-Y0-Z0 is the one whose reference is the hull of the vessel. Each of these coordinate systems is a right-handed system. Because located on the surface of the earth, the position of a vessel sailing on the sea of the earth or on the water surface of a river or a lake undergoes the effect of the spherical earth. However, when the distance between the vessel **1** and the fixed point on the ground that is 0 m above sea level or on the water is small, the situation can be considered in a simplified manner by assuming that both the fixed point and the vessel **1** are on one and the same plane.

In the coordinate system X1-Y1-Z1 whose reference is a fixed point on the ground that is 0 m above sea level or on the water, X1 denotes the north-south direction (the arrow indicates the north); Y1 denotes the east-west direction (the arrow indicates the east). Z1 denotes the vertical direction (the arrow indicates the bottom). The vessel **1** is located on the X1-Y1 plane; in the coordinate system X0-Y0-Z0 whose reference is the vessel, X0 denotes the anteroposterior direction passing through the gravity center of the vessel (the arrow indicates the front, i.e., the bow direction); Y0 denotes the left-and-right direction passing through the gravity center of the vessel (the arrow indicates the right, i.e., the starboard direction); Z0 denotes the vessel-structure vertical direction passing through the gravity center of the vessel (the arrow indicates the bottom).

A yaw angle YA (referred to also as an azimuth angle) is a rotation angle around the Z0 axis. A yaw angular velocity (yaw rate) is a rotation angular velocity around the Z0 axis.

In the case where the azimuth to which the vessel should travel is instructed by the azimuth command generation unit **100**, the azimuth command signal DRC is indicated with respect to the X1 direction (the north, in FIG. 2) in the coordinate system X1-Y1-Z1 whose reference is a fixed point on the ground that is 0 m above sea level or on the

water. The direction of the hull of the vessel 1 is indicated by a yaw angle with respect to the X1 direction. For example, in the case where it is instructed that the vessel should travel in the northeast, the vessel is operated in such a way as to maintain the yaw angle YA of 45° clockwise with respect to the north, which is the X1 direction.

In the case where the distance between the vessel 1 and the fixed point on the ground that is 0 m above sea level or on the water is large, it cannot simply be considered that both the fixed point and the vessel 1 are on one and the same plane; thus, it is required to make calculation while taking it into consideration that the earth is a sphere. Also in this case, the vessel is operated in such a way as to maintain the yaw angle instructed with respect to the north on the water surface on which the vessel is located.

<Flowchart Representing Basic Operation>

FIG. 4 is a flowchart representing basic operation of the azimuth control apparatus 10 according to Embodiment 1. The azimuth control unit 200 obtains the vessel parameters, based on an instruction from the operational device 30 or a determination by the azimuth control unit 200 itself, so as to adjust the control gain.

Because in the initial state, a reference transfer function has been set, the azimuth control unit 200 can calculate the steering-angle command signal RUAC, based on the instruction from the azimuth command generation unit 100, without performing adjustment. However, when the respective frequency responses of the yaw-angle signal Y and the yaw-angular-velocity signal YR to the steering-angle signal RUA for the vessel 1 are obtained, the control gain of the azimuth control unit 200 can be adjusted in accordance with the newest state of the vessel 1.

The flowchart in FIG. 4 is implemented each time the azimuth control apparatus 10 obtains the vessel parameters so as to adjust the control gain. In the step S100, during sailing, there is outputted a steering-angle command, in the shape of a rectangular wave or a saw-tooth wave, that is the steering-angle command signal RUAC from the azimuth control unit 200, a steering-angle command, in an arbitrary shape, that is manually generated by a vessel operator by use of a steering wheel or the like, or a steering-angle command calculated by the azimuth control unit 200 based on the azimuth command signal DRC at a time of normal sailing.

In the step S101, the frequency response calculation unit 400 obtains respective time-series data of the yaw-angle signal Y and the yaw-angular-velocity signal YR to the steering-angle signal RUA. The frequency response calculation unit 400 calculates the frequency response as vessel characteristic information FC. In this situation, it may be allowed that data of the vessel-speed signal V is concurrently obtained so that the frequency response corresponding to the vessel speed is calculated.

In the step S103, target response-performance information TC is read. The target response-performance information TC is preliminarily determined for the vessel 1; the basic reference transfer function is set from the target response-performance information TC.

In the step S104, by use of the frequency response (vessel characteristic information FC) calculated in the step S101, control gain information GI is calculated based on the reference transfer function set from the target response-performance information TC. In the step S105, by use of the control gain information GI, the azimuth control unit 200 performs an azimuth control calculation so as to output the steering-angle command signal RUA. In response to the steering-angle command signal RUAC, the steering-angle control unit 600 outputs the steering-angle driving command

signal RUAD so as to control the steering-angle driving unit 40; as a result, the azimuth of the vessel 1 is controlled. In this situation, it may be allowed that in the steps S101 through S105, data of the vessel-speed signal V is concurrently obtained so that the control gain information GI corresponding to the vessel speed is calculated.

The respective functions of the azimuth command generation unit 100, the azimuth control unit 200, the gain adjusting unit 300, and the frequency response calculation unit 400 included in the vessel azimuth control apparatus 10 will be explained in detail.

<Azimuth Command Generation Unit>

FIG. 5 is a block diagram representing the configuration of the azimuth command generation unit 100 of the azimuth control apparatus 10 according to Embodiment 1. The azimuth command generation unit 100 includes a motion condition setting unit 101 and an azimuth calculation unit 102. The motion condition setting unit 101 sets an initial condition and a terminal condition for sailing of a vessel 1; when a vessel operator performs inputting to the operational device 30 of the vessel 1, the initial condition and the terminal condition are set through the operation information CI.

By means of the operational device 30 of the vessel 1, the vessel operator sets information items on a posture angle (a synonym of an azimuth angle or a yaw angle), an angular velocity (a value obtained through a single time differentiation of the posture angle), and an angular acceleration (a value obtained through a double time differentiation of the posture angle) in each of an initial state before sailing starts and a terminal state when a desired sailing has been completed. It may be allowed that the condition setting is performed with values obtained by converting the posture angle, the angular velocity, and the angular acceleration into numerals. The setting can be performed by use of a user interface in which a GNSS is provided as a touch panel. The setting may be performed in such a way that with regard to the initial state, a detection value of the sensor group 20 is automatically taken in, as sensor-group information, and only the terminal state is touch-inputted by use of a user-interface screen.

The azimuth calculation unit 102 receives initial-state information SCI and terminal-state information ECI outputted by the motion condition setting unit 101 and then calculates the azimuth command signal DRC. In this situation, two or more calculation methods for the azimuth command signal DRC are conceivable. For example, a provided orbit can be calculated as a time polynomial, based on the posture angle, the angular velocity, and the angular acceleration in each of the initial-state information SCI and the terminal-state information ECI of the vessel 1, obtained by the motion condition setting unit 101.

In addition, it is also made possible to calculate a linear orbit that connects the initial-state information SCI with the terminal-state information ECI in the shortest time. It is also made possible to calculate an orbit through which the vessel can travel from the initial state to the terminal state with a minimum quantity of fuel. That is to say, it may be allowed that when the initial state transits to the terminal state, the orbit is calculated as an optimum orbit that minimizes a preliminarily set evaluation function, for example, as an optimum orbit in terms of a shortest time or in terms of a minimum quantity of fuel.

<Azimuth Control Unit>

FIG. 6 is a block diagram representing the configuration of the azimuth control unit 200 of the azimuth control apparatus 10 according to Embodiment 1. The azimuth

control unit 200 includes a control calculation unit 210 and a sensor-information processing unit 220. The sensor-information processing unit 220 outputs the yaw-angle signal Y and the yaw-angular-velocity signal YR, which are the outputs of the sensor group 20, to the control calculation unit 210. In this situation, it may be allowed that data of the vessel-speed signal V is concurrently obtained and then is outputted to the control calculation unit 210.

The sensor-information processing unit 220 may have a function of converting information pieces of the various kinds of sensors, which are serial signals transmitted from the sensor group into parallel signals. In addition, the sensor-information processing unit 220 may have a function of generating the yaw-angular-velocity signal YR by time-differentiating the yaw-angle signal Y.

The control calculation unit 210 outputs the steering-angle command signal RUAC to the steering-angle control unit 600, based on the azimuth command signal DRC, which is the output of the azimuth command generation unit 100, the control gain information GI (GI1, GI2, GI3), which is the output of the gain adjusting unit 300, and the yaw-angle signal Y and the yaw-angular-velocity signal YR, which are the outputs of the sensor-information processing unit 220. In this situation, it may be allowed that the control gain is concurrently switched in accordance with the data of the vessel-speed signal V and the steering-angle command signal RUAC is calculated and outputted.

<Control Calculation Unit>

FIG. 7 is a block diagram representing the configuration of the control calculation unit 210 of the azimuth control apparatus 10 according to Embodiment 1. The control calculation unit 210 includes a first control calculation unit 211, a second control calculation unit 212, a third control calculation unit 213, and an adder 214.

By means of a publicly known P (Proportional)-control utilizing the first control gain information GI1, the first control calculation unit 211 calculates the yaw-angular-velocity command signal YRC in such a way that the difference between the azimuth command signal DRC and the yaw-angle signal Y becomes zero, and then outputs the yaw-angular-velocity command signal YRC. By means of a publicly known PI (Proportional Integral)-control utilizing the second control gain information GI2, the second control calculation unit 212 calculates an FB (Feedback) steering-angle command FBC in such a way that a yaw-angular velocity difference between the yaw-angular-velocity command signal YRC, which is the output of the first control calculation unit 211, and the yaw-angular-velocity signal YR becomes zero, and then outputs the FB steering-angle command FBC.

Based on the yaw-angular-velocity command signal YRC, which is the output of the first control calculation unit 211, and the third control gain information GI3, the third control calculation unit 213 calculates an FF (Feedforward) steering-angle command FFC, and then outputs the FF steering-angle command FFC. The adder 214 adds the FF steering-angle command FFC, which is the output of the third control calculation unit 213, to the FB steering-angle command FBC, which is the output of the second control calculation unit 212.

The adder 214 outputs the steering-angle command signal RUAC, as the result of the addition. Such a configuration of the control calculation unit 210 makes it possible that the first control calculation unit 211 and the second control calculation unit 212 raise the azimuth stability and that the third control calculation unit 213 raises the azimuth responsiveness. It may be allowed that the first control calculation

unit 211, the second control calculation unit 212, and the third control calculation unit 213 concurrently switch the respective control gains in accordance with the data of the vessel-speed signal V and then output the corresponding signal and commands.

<Control Gain Adjustment Unit>

FIG. 8 is a block diagram representing the configuration of the gain adjusting unit 300 of the azimuth control apparatus 10 according to Embodiment 1. In general, azimuth motion of the vessel 1 can be characterized as the frequency response of the yaw-angular-velocity signal YR to the steering-angle signal RUA. For example, in Patent Document 1, as the frequency response of the yaw-angular-velocity signal YR to the steering-angle signal RUA, a linear model is dealt with.

However, the frequency response of the vessel 1 largely changes depending on a motion state of the vessel 1, for example, the speed of the vessel (vessel speed, hereinafter); for example, in the case where the steering angle is turned by a predetermined amount at predetermined speed, the yaw-angular-velocity signal YR is small in a low-vessel-speed region and large in a high-vessel-speed region. Accordingly, in order to diminish unevenness in the control response, depending on the vessel speed, and to make the crossover frequency determining the response of a control system stay constant regardless of the vessel speed, it is required that the control gain information to be inputted to the control calculation unit 210 can be changed in accordance with the vessel speed.

FIG. 9 is a chart representing vessel characteristic information of the azimuth control apparatus 10 according to Embodiment 1. FIG. 9 represents the frequency response of the yaw-angular-velocity signal YR to the steering-angle signal RUA, with regard to the gain and the phase thereof. In the low-speed region (represented by a solid line) where the vessel speed is low, the frequency response has a characteristic that can readily be approximated with a linear model. However, in the high-speed region (represented by a broken line) where the vessel speed is high, the gain increases; concurrently, the frequency response has a gentle peak gain at the high-frequency side, depending on conditions, and hence cannot be approximated with a linear model. FIG. 9 represents the frequency response of the yaw-angular-velocity signal YR; however, the above description can be applied to the yaw-angle signal Y.

In order to appropriately design or set the control gain information GI in the control calculation unit 210 in accordance with the vessel speed, the gain adjusting unit 300 calculates the control gain information GI, based on the vessel characteristic information and the target response-performance information TC, which are the outputs of the after-mentioned frequency response calculation unit 400, and then outputs the control gain information GI. The gain adjusting unit 300 represented in FIG. 8 includes a reference transfer function setting unit 301 and an online gain adjusting unit 302.

Based on the arbitrarily selected target response-performance information TC, for example, the gain crossover frequency, the reference transfer function setting unit 301 outputs a reference transfer function representing the frequency response of the yaw-angle signal Y to the steering-angle signal RUA and a reference transfer function representing the frequency response of the yaw-angular-velocity signal YR to the steering-angle signal RUA for achieving a target response performance. Then, the online gain adjusting unit 302 calculates and outputs the control gain information pieces GI (GI1, GI2, and GI3) related to the first through

third control calculation units (211 through 213) in the foregoing control calculation unit 210.

Based on the vessel characteristic information FC, which is the output of the after-mentioned frequency response calculation unit 400, and the reference transfer function, which is the output of the reference transfer function setting unit 301, the online gain adjusting unit 302 calculates the control gain information pieces GI1 and GI2 related to the first and second control calculation units 212 and 212, respectively, through a publicly known partial model matching method, for example.

In contrast, based on the vessel characteristic information, the online gain adjusting unit 302 calculates the control gain information GI3 related to the third control calculation unit 213, by use of, for example, the frequency response of the steering-angle signal RUA to the yaw-angular-velocity signal YR, which is an inverse model of the frequency response of the yaw-angular-velocity signal YR to the steering-angle signal RUA. In this situation, in the case where the foregoing inverse model includes a high-order time differentiation, for example, a double time differentiation, it may be allowed that in order to suppress the FF steering-angle command FFC, which is the output of the third control calculation unit 213, from steeply changing, a low-pass filter or moving-average processing is provided after the inverse model. In addition, it may be allowed that approximation processing for reducing the order of the inverse model itself is adopted.

It may also be allowed that as an input of the gain adjusting unit 300 in FIG. 8, data of the vessel-speed signal V is concurrently added and the control gain corresponding to the vessel speed is obtained.

<Frequency Response Calculation Unit>

FIG. 10 is a block diagram representing the configuration of the frequency response calculation unit 400 of the azimuth control apparatus 10 according to Embodiment 1. The frequency response calculation unit 400 inputs the vessel characteristic information FC to the gain adjusting unit 300. In general, the frequency response of the azimuth motion of the vessel 1 changes in accordance with the vessel speed.

It is conceivable that this frequency response is obtained, for example, from the amplification factor of the response of the yaw-angular-velocity signal YR to the steering-angle signal RUA and the phase difference therebetween at a time when the sine-wave steering-angle command signal RUAC is applied in such a way as to be frequency-swept while the vessel 1 is sailing at constant speed. However, because it requires massive measurement time and memory capacity for obtaining low-frequency characteristics, this method is not suitable to estimate online the vessel characteristic information FC that characterizes the foregoing frequency response.

In contrast, the frequency response calculation unit 400 receives sensor-group information, which is the output of the sensor group 20 at a time when as the steering-angle command signal RUAC, a rectangular wave signal or a saw-tooth wave signal having sufficient power within a noteworthy band width in the frequency response is applied for a predetermined time, and then estimates online and outputs the vessel characteristic information. The frequency response calculation unit 400 includes a data processing unit 401 and a recursive estimation filter unit 402.

The data processing unit 401 is a filter for eliminating observation noise signals superimposed on the steering-angle signal RUA, the yaw-angular-velocity signal YR, and the vessel-speed signal V, based on the sensor-group information, which is the output of the sensor group 20. The outputs of the data processing unit 401 are respective

processed data pieces of the steering-angle signal RUA, the yaw-angular-velocity signal YR, and the vessel-speed signal V.

<Calculation Feasibility Determination Unit>

The calculation feasibility determination unit 403 determines based on, for example, the sensor-group information, which is the output of the sensor group 20, whether or not data pieces obtained by calculating the amplitude of each of the steering-angle signal RUA, the yaw-angular-velocity signal YR, and the yaw-angle signal Y or the degree of correlation among them are adequate for calculating the frequency response. Then, the calculation feasibility determination unit 403 outputs determination information PC.

It may be allowed that the condition of adequate data for calculating the frequency response is, for example, that the SN ratio, which is the ratio of the sensor signal to the sensor noise, is sufficiently high or that the fluctuation thereof due to irregular disturbance such as a wave is smaller than the amplitude of the sensor signal. It may be allowed that the condition on which whether or not the data is adequate for calculating the frequency response is determined is whether or not the amplitude (absolute value) of the steering-angle signal or the steering-angle command signal exceeds a threshold value or whether or not the amplitude (absolute value) of a steering-angle speed signal or a steering-angle-speed command signal, which is the difference between the steering-angle signal or the steering-angle command signal, exceeds a threshold value. In addition, it may be allowed that the foregoing condition is whether or not the value of a correlation coefficient, obtained sequentially from the yaw-angular-velocity signal and the steering-angle signal or the steering-angle speed signal, exceeds a threshold value.

In addition, the foregoing threshold values may be changed in accordance with the vessel speed. In general, the lower the vessel speed is, the lower the SN ratio becomes, and hence the effect of fluctuation due to a disturbance such as a wave becomes large. Accordingly, when the vessel speed is low, it may be allowed that the threshold value is increased so as to relax the condition for determination of the calculation feasibility. In the case where as the method of selecting the threshold value, the steering angle or the steering-angle speed signal is utilized, there can be adopted an empirical value with which the yaw angular velocity allegedly becomes sufficiently large. In the case where a correlation coefficient is utilized, a value between 0.7 and 1.0 may be utilized.

The recursive estimation filter unit 402 outputs a vessel characteristic information candidate RFC and estimation accuracy information PR for the vessel characteristic information candidate RFC, based on the processed data pieces, which are the outputs of the data processing unit 401, and the determination information PC, which is the output of the calculation feasibility determination unit 403. For example, by use of a publicly known sequential least square method, the recursive estimation filter unit 402 sequentially estimates a model for the frequency response of the yaw-angular-velocity signal YR to the steering-angle signal RUA, and then outputs the model as the vessel characteristic information candidate RFC. In addition, in the process where the frequency-response model is estimated, there can concurrently be obtained the variance of the estimation value in the model, a predictive error amount, and the like. The variance, the predictive error amount, or the like is outputted as the estimation accuracy information PR.

As described above, in the high-speed region where the vessel speed is high, a peak gain may occur at the high-frequency side. Accordingly, in order to deal with such a

high-speed region where a peak gain occurs, the order of the frequency-response model is raised up to the second or higher and then the model for the frequency response of the yaw-angular-velocity signal YR to the steering-angle signal RUA is sequentially estimated. The frequency-response model for the frequency response of the yaw-angle signal Y to the steering-angle signal RUA may be estimated in the same manner.

<Steering-Angle Offset Amount>

In the case where the vessel sails straightforward while undergoing a disturbance of a tidal current or wind in the transverse direction thereof, it is required to maintain the steering angle at a predetermined angle. The foregoing steering-angle amount will be referred to as a steering-angle offset amount RUA0. In the case where the steering-angle offset amount RUA0 is large, the frequency-response model representing the dynamic characteristic of a vessel cannot sufficiently express the behavior of the vessel. Accordingly, an example of an ARX (Auto-Regressive exogenous) model where the steering-angle offset amount RUA0 is taken into consideration is expressed by a difference equation below.

$$YR[k] = A1 \times YR[k-1] + A2 \times YR[k-2] + B1 \times (U[k-1] - U0) + B2 \times (U[k-2] - U0)$$

where A1, A2, B1, and B2 denote parameters indicating the dynamic characteristics of a vessel, U0 denotes the steering-angle offset amount, YR denotes the yaw angular velocity, U denotes the steering-angle amount, and K, K-1, K-2 denote data sampling numbers.

When a vessel undergoes a disturbance in the transverse direction and the steering-angle offset amount U0 is not zero, this model can express that the respective yaw angular velocities at a time when the steering angle U is a constant value of 10 deg. and at a time when the steering angle is a constant value of -10 deg. converge at different values. Accordingly, by utilizing a model where the steering-angle offset amount is explicitly considered, the steering-angle offset amount can be estimated.

For example, by use of the publicly known sequential least square method, the parameters A1, A2, B1, and B2 indicating parameters representing the dynamic characteristics and the steering-angle offset amount U0 representing the static characteristics can sequentially be estimated. In addition, because the steering-angle offset amount U0 can sequentially be estimated, the parameters A1, A2, B1, and B2 and the steering-angle offset amount U0 can adequately and sequentially be estimated, even when the azimuth largely changes during sailing and hence the direction of the disturbance to the vessel changes and even when the strength of the disturbance increases or decreases.

The model to be utilized in the recursive estimation filter unit 402 is not limited to the foregoing quadratic ARX model. For example, the vessel characteristic information candidate RFC and the estimation accuracy information PR can be outputted by use of any one of various models such as a linear ARX model, a differential equation model, and a state space model.

Moreover, the estimation method to be utilized in the recursive estimation filter unit 402 is not limited to the foregoing sequential least square method. The vessel characteristic information candidate RFC can be obtained by use of any one of various recursive estimation methods such as a publicly known Kalman filter, an extended Kalman filter, a Kalman smoother, and a sequential subspace identification method. The variance and the predictive error amount of the estimation value can be estimated by the exemplified pub-

licly known recursive estimation method and hence can be outputted as the estimation accuracy information PR.

In addition, it is made possible that based on the determination information PC, which is the output of the calculation feasibility determination unit 403, part of or all of the calculation algorithm of the foregoing recursive estimation method is stopped or changed and then the vessel characteristic information candidate RFC can sequentially be calculated by use of only the data suitable for the calculation.

For example, in the case where the steering angle is hardly changed, the parameters representing the dynamic characteristics cannot adequately be estimated; thus, an inadequate vessel characteristic information candidate RFC may be calculated.

However, the foregoing function can extract only the data with which the parameters representing the dynamic characteristics can adequately be estimated. As a result, the adequate vessel characteristic information candidate RFC can be calculated. In addition, in the case where the calculation algorithm is stopped or changed, some variables in the calculation algorithm have a forgetting function, so that when the time of stopping or changing is long, the estimation can be restarted without being affected by the previous estimation information.

The foregoing function makes it possible to adequately calculate the vessel characteristic information candidate RFC, without applying the rectangular-wave or saw-tooth-wave steering-angle command signal RUAC, which is alleged to be suitable for estimation of the dynamic characteristics. By use of the steering-angle command signal RUAC manually generated by a vessel operator or by use of the steering-angle command signal RUAC calculated by the azimuth control unit 200, based on the azimuth command signal DRC at a time of normal sailing, it is made possible that only the data suitable for the calculation is automatically extracted and then the vessel characteristic information candidate RFC is calculated. As a result, the adequate vessel characteristic information candidate RFC can be calculated.

<Characteristic Learning Unit>

Based on the vessel characteristic information candidate RFC, which is the output of the recursive estimation filter unit 402, and the estimation accuracy information PR, the characteristic learning unit 404 learns the vessel characteristic information candidate RFC at a time when the estimation accuracy information PR is satisfactory and then outputs it as the vessel characteristic information FC. The characteristic learning unit 404 learns the vessel characteristic information FC each time the estimation accuracy information PR exceeds a predetermined threshold value. In addition, after the calculation of the vessel characteristic information candidate RFC is started, the vessel characteristic information FC is held at a default value (an initial setting value) until the estimation accuracy information PR exceeds the threshold value, so that low-accuracy vessel characteristic information FC can be prevented from being outputted.

Moreover, when the characteristic learning unit 404 learns the vessel characteristic information FC, based on the vessel characteristic information candidate RFC, it may be allowed that the vessel characteristic information candidate RFC is reflected in the vessel characteristic information FC by means of an averaging method including a first-order lag element. For example, the foregoing equation may be utilized for the calculation.

$$FC(n) = K \times RFC + (1-K) \times FC(n-1)$$

Where K denotes a reflection coefficient of the same as or larger than 0 but the same as or smaller than 1, FC(n) denotes vessel characteristic information calculated at the present time, and FC(n-1) denotes vessel characteristic information calculated at the immediately previous time.

Moreover, it may be allowed that in the learning by the characteristic learning unit 404, the rate of the reflection of the vessel characteristic information candidate RFC is changed in accordance with the value of the estimation accuracy information PR. For example, it may be allowed that the value of the reflection coefficient is set in such a way as to become larger as the value of the estimation accuracy information PR becomes larger.

In this situation, when the estimated frequency-response model is associated with the vessel speed, which is the output of the data processing unit 401, the vessel characteristic information FC can be accumulated, as a function of the vessel speed or a map, in the characteristic learning unit 404. Accumulation of the vessel characteristic information FC in the characteristic learning unit 404 makes it possible to immediately cope with a case where the vessel speed changes or a case where the target response-performance information TC is changed. It is made possible that based on the vessel characteristic information FC accumulated in the characteristic learning unit 404, the control gain information GI is adequately designed or set, without re-estimating the frequency response.

Moreover, the vessel characteristic information FC to be learned by the characteristic learning unit 404 may have learning values divided into two or more zones in accordance with the yaw-angle signal Y, the yaw-angular-velocity signal YR, the steering-angle signal RUA, and the like. Minute setting of two or more learning values in such a manner makes it possible to utilize the optimum target response-performance information TC corresponding to the yaw-angle signal Y, the yaw-angular-velocity signal YR, the steering-angle signal RUA, and the like.

As described above, there has been explained the vessel azimuth control apparatus 10, according to Embodiment 1, that makes the vessel 1 sail to a desired azimuth. The azimuth control apparatus 10 has the azimuth command generation unit 100 that outputs the azimuth command signal DRC, the frequency response calculation unit 400 that receives sensor-group information from the sensor group 20 mounted in a vessel and outputs the vessel characteristic information FC, and the gain adjusting unit 300 that outputs the control gain information GI, based on the vessel characteristic information FC, which is the output of the frequency response calculation unit 400. The azimuth control unit 200 outputs the steering-angle command signal RUAC, based on the azimuth command signal DRC, which is the output of the azimuth command generation unit 100, the control gain information GI from the gain adjusting unit 300, and sensor-group information from the sensor group 20.

Accordingly, during sailing, there can be calculated vessel parameters for calculating a control gain with which satisfactory veering characteristics are obtained for an arbitrary steering pattern at a time of normal sailing, while considering a change in the azimuth and the effect of disturbance that changes from moment to moment. Accordingly, it is made possible to instantaneously calculate an adequate control gain for an error in modeling the control subject that can change. As a result, it is made possible to perform robust designing for a change in the characteristics of the control subject and to appropriately adjust the disturbance suppression performance and the target value response performance related to the azimuth control. Moreover, it is made possible

to realize stable azimuth control, without promoting a vibration excited by a disturbance factor, such as a tidal current, an ocean wave, or a storm, applied to the vessel.

5 2. Embodiment 2

FIG. 11 is a configuration diagram of an azimuth control apparatus 10a according to Embodiment 2. FIG. 12 is a block diagram representing the configuration of frequency response calculation unit 400a of the azimuth control apparatus 10a according to Embodiment 2.

The azimuth control apparatus 10a according to Embodiment 2 represented in FIG. 11 differs from the azimuth control apparatus 10 according to Embodiment 1 in that the steering-angle driving command signal RUAD to be inputted to the steering-angle driving unit 40 is outputted by the steering-angle control unit 600 that receives the steering-angle offset amount RUA0 outputted by the frequency response calculation unit 400a provided in the control gain adjustment unit 500a and the steering-angle command signal RUAC outputted by the azimuth control unit 200. Other configurations are the same as those in FIG. 1; therefore, explanations therefore will be omitted.

FIG. 12 is a block diagram representing the configuration 25 of frequency response calculation unit 400a of the azimuth control apparatus 10a according to Embodiment 2. The frequency response calculation unit 400a includes the data processing unit 401, a recursive estimation filter unit 402a, the calculation feasibility determination unit 403, and the characteristic learning unit 404. In Embodiment 1, the output of the recursive estimation filter unit 402 is the vessel characteristic information candidate RFC. In contrast, in Embodiment 2, the steering-angle offset amount RUA0 to be estimated along with the vessel characteristic information candidate RFC is outputted to the steering-angle control unit 600a. The steering-angle control unit 600a outputs the steering-angle driving command signal RUAD, obtained in consideration of the steering-angle offset amount RUA0, so as to perform azimuth control.

Such a configuration as described above makes it possible to output the steering-angle driving command signal RUAD that cancels out a disturbance caused by the steering-angle offset amount RUA0. Accordingly, the responsiveness and the stability are prevented from being deteriorated by a disturbance caused through the steering-angle offset amount RUA0; thus, the azimuth control performance can be raised.

3. Embodiment 3

FIG. 13 is a configuration diagram of an azimuth control apparatus 10b according to Embodiment 3. FIG. 14 is a block diagram representing the configuration of frequency response calculation unit 400b of the azimuth control apparatus 10b according to Embodiment 3.

The azimuth control apparatus 10b according to Embodiment 3 represented in FIG. 13 differs from the azimuth control apparatus according to Embodiment 2 in that the frequency response calculation unit 400b provided in a control gain adjustment unit 500b is different from the frequency response calculation unit 400a. The frequency response calculation unit 400b according to Embodiment 3 represented in FIG. 14 differs from the azimuth control apparatus 400a according to Embodiment 2 in that the steering-angle offset amount RUA0 outputted by the recursive estimation filter unit 402a is inputted to a calculation feasibility determination unit 403a so as to be reflected in the determination information PC. Other configurations are the

same as those in FIGS. 11 and 12; therefore, they are designated by the same reference numerals and the explanations therefor will be omitted.

In each of Embodiments 1 and 2, the calculation feasibility determination unit 403 calculates the respective absolute values or correlation coefficients of the steering-angle signal RUA, the yaw-angle signal Y, the yaw-angular-velocity signal YR, and the like and then outputs determination information. In contrast, in Embodiment 3, the determination information is outputted by use of a signal obtained by superimposing the steering-angle offset amount RUA0 on the steering-angle signal RUA. Accordingly, the correlations and the like with the yaw-angle signal Y, the yaw-angular-velocity signal YR, and the like to be utilized in the determination by the calculation feasibility determination unit 403 can more accurately be obtained. Such a configuration as described above makes it possible that even when the steering-angle offset amount RUA0 is large, more adequate data for estimating the dynamic characteristics can be extracted; thus, the more accurate vessel characteristic information candidate RFC can be outputted.

In foregoing Embodiments 1, 2, and 3, it may be allowed that the azimuth command generation unit 100, the azimuth control unit 200, the gain adjusting unit 300, the frequency response calculation units 400 and 400a, and the steering-angle control units 600 and 600a in the corresponding azimuth control apparatuses 10a, and 10b represented in FIGS. 1, 11, and 13, respectively, and the control blocks that are included in the respective foregoing units and have the respective functions represented in FIGS. 4 through 8 and FIGS. 10 through 14 are configured with separate control circuits. Alternatively, it may be allowed that all of these units are collectively configured with a single control circuit.

Moreover, it may be allowed that the foregoing control blocks are integrated while including the steering-angle driving mechanism that controls the steering angle of an outboard engine or an inboard engine. The processing circuit for realizing these functions may be dedicated hardware. Each of these functions can also be configured with a CPU (referred to also as a central processing unit, a processing device, a calculation apparatus, a microprocessor, a micro-computer, a processor, a DSP, or the like).

In the case where the control portion in each of the vessel azimuth control apparatuses 10, 10a, and 10b in Embodiments 1, 2, and 3, respectively, is configured with software, the function of each of the control portions in the respective embodiments may be realized by software of the type where each time software is executed, it is downloaded on a memory before being executed. In addition, the function of each of the control portions may be realized by firmware fixed in the nonvolatile storage apparatus of a computer or by a combination of the software of the foregoing type and the firmware.

The software and the firmware of the foregoing types are each described as programs and are stored in memories. The processor, which is a processing circuit, reads and executes the program stored in the memory so as to realize the function of each of the respective units. These programs make the computer execute the respective procedures and methods of the foregoing units. In this situation, a nonvolatile or volatile semiconductor memory such as a RAM, a ROM, a flash memory, an EPROM, or an EEPROM, a magnetic disk, a flexible disk, an optical disk, a compact disk, a minidisk, a DVD, or the like is suitable for the foregoing memory.

In addition, it may be allowed that the function of each of the foregoing respective control blocks is realized partially

by dedicated hardware and partially by the software or firmware of the foregoing type. As described above, the function of the processing circuit in each of the embodiments can be realized by hardware, the software or the firmware of the foregoing type, or a combination of these constituent elements. In the case of a hardware configuration, various kinds of information items required for the processing are preliminarily set in the circuit; in the case of a software configuration, the various kinds of information items are preliminarily stored in the memory.

As a matter of course, it is made possible that in each of the foregoing embodiments, the control calculation unit is configured only with an angular major loop, with a double loop including an angular major loop and an angular-velocity minor loop, or with a triple loop including an angular major loop, an angular-velocity minor loop, and an angular-acceleration minor loop. In this situation, the angular acceleration may be obtained either by applying two-time differentiation to the yaw-angle signal Y, which is one of the sensor-group information items, or by applying one-time differentiation to the yaw-angular-velocity signal YR. Furthermore, in each of the embodiments, as the configuration of the controller, not only a classic control system but also a modern control system for state-feedback control can be utilized.

Although the present application is described above in terms of various exemplary embodiments and implementations, it should be understood that the various features, aspects and functions described in one or more of the individual embodiments are not limited in their applicability to the particular embodiment with which they are described, but instead can be applied, alone or in various combinations to one or more of the embodiments. Therefore, an infinite number of unexemplified variant examples are conceivable within the range of the technology disclosed in the specification of the present disclosure. For example, there are included the case where at least one constituent element is modified, added, or omitted and the case where at least one constituent element is extracted and then combined with constituent elements of other embodiments.

Hereinafter, respective features disclosed in the present disclosure will collectively be described as appendixes.

(Appendix 1) A vessel azimuth control apparatus comprising:

- 45 an azimuth command generation unit that generates an azimuth command signal indicating an azimuth to which a vessel should travel;
- a yaw-angle detection unit that outputs a yaw-angle signal indicating a rotation angle around a vertical axis passing through a gravity center of the vessel;
- a yaw-angular-velocity detection unit that outputs a yaw-angular-velocity signal indicating a rotation angular velocity around the vertical axis passing through the gravity center of the vessel;
- a steering-angle detection unit that outputs a steering-angle signal indicating an angle of a rudder of the vessel;
- a vessel-speed detection unit that outputs a vessel-speed signal indicating a vessel speed of the vessel;
- an azimuth control unit that outputs a steering-angle command signal for making the vessel turn to the azimuth to which the vessel should travel, based on the azimuth command signal generated by the azimuth command generation unit, the yaw-angle signal outputted by the yaw-angle detection unit, and the yaw-angular-velocity signal outputted by the yaw-angular-velocity detection unit;

a steering-angle control unit that control a rudder, based on the steering-angle command signal outputted by the azimuth control unit; and

a control gain adjustment unit that has a calculation feasibility determination unit for determining feasibility of calculation of frequency responses, based on the yaw-angle signal and the yaw-angular-velocity signal, and that calculates respective frequency responses of the yaw-angle signal and the yaw-angular-velocity signal for the steering-angle signal outputted by the steering-angle detection unit, when the calculation feasibility determination unit determines that calculation of frequency responses are feasible, and then adjusts a control gain of the azimuth control unit.

(Appendix 2) The vessel azimuth control apparatus according to claim 1, wherein the calculation feasibility determination unit of the control gain adjustment unit determines feasibility of calculation of the frequency responses, based on at least one of a degree of correlation among the steering-angle signal, the yaw-angle signal, and the yaw-angular-velocity signal, respective amplitudes thereof, respective changing amounts thereof, respective signal-to-noise ratios thereof, and respective fluctuation ratios thereof to disturbance.

(Appendix 3) The vessel azimuth control apparatus according to claim 2, wherein in accordance with the vessel-speed signal, the calculation feasibility determination unit of the control gain adjustment unit changes a comparison threshold value for determining feasibility of calculation of the frequency responses, based on at least one of a degree of correlation among the steering-angle signal, the yaw-angle signal, and the yaw-angular-velocity signal, respective amplitudes thereof, respective changing amounts thereof, respective signal-to-noise ratios thereof, and respective fluctuation ratios thereof to disturbance.

(Appendix 4) The vessel azimuth control apparatus according to any one of claims 1 through 3, wherein the calculation feasibility determination unit of the control gain adjustment unit permits calculation of the frequency responses, when a changing amount of the steering-angle signal is larger than a predetermined changing amount.

(Appendix 5) The vessel azimuth control apparatus according to any one of claims 1 through 4, wherein the control gain adjustment unit calculates a calculation accuracy, when respective frequency responses of the yaw-angle signal and the yaw-angular-velocity signal for the steering-angle signal are calculated, and adjusts a control gain of the azimuth control unit, based on the frequency response calculated at a time when the calculation accuracy is higher than a predetermined accuracy.

(Appendix 6) The vessel azimuth control apparatus according to claim 5, wherein the control gain adjustment unit learns the frequency responses calculated at a time when the calculation accuracy is higher than a predetermined accuracy.

(Appendix 7) The vessel azimuth control apparatus according to claim 6, wherein the control gain adjustment unit applies weighting corresponding to the calculation accuracy to the calculated frequency responses and then learns the weighted frequency responses.

(Appendix 8) The vessel azimuth control apparatus according to any one of claims 1 through 7, wherein the control gain adjustment unit calculates a steering-angle offset amount that is a counter-steering amount at a time of straight sailing and then adjusts a control gain of the azimuth control unit.

(Appendix 9) The vessel azimuth control apparatus according to claim 8, wherein the control gain adjustment unit calculates the steering-angle offset amount by a difference equation, based on a model where the steering-angle offset amount is explicitly expressed.

(Appendix 10) The vessel azimuth control apparatus according to any one of claims 8 and 9, wherein the steering-angle control unit that controls a rudder, based on the steering-angle command signal and the steering-angle offset amount.

(Appendix 11) The vessel azimuth control apparatus according to any one of claims 8 through 10, wherein the calculation feasibility determination unit of the control gain adjustment unit determines feasibility of calculation of the frequency responses, based on the steering-angle signal and the steering-angle offset amount.

(Appendix 12) The vessel azimuth control apparatus according to any one of claims 1 through 11, wherein the azimuth control unit includes

a first control calculation unit that calculates a yaw-angular-velocity command signal for making a difference between the azimuth command signal and the yaw-angle signal become zero,

a second control calculation unit that calculates a feedback steering-angle command signal for making a difference between the yaw-angular-velocity command signal calculated by the first control calculation unit and the yaw-angular-velocity signal become zero,

a third control calculation unit that calculates a feed-forward steering-angle command signal, based on the yaw-angular-velocity command signal, and

an adder that adds the feedback steering-angle command signal calculated by the second control calculation unit and the feed-forward steering-angle command signal calculated by the third control calculation unit and then outputs a steering-angle command signal.

(Appendix 13) The vessel azimuth control apparatus according to any one of claims 1 through 12, wherein the control gain adjustment unit includes

a reference transfer function setting unit that sets a yaw-angle-signal reference transfer function having target frequency responses for the yaw-angle signal and a yaw-angular-velocity-signal reference transfer function having target frequency responses for the yaw-angular-velocity signal, with regard to the steering-angle signal, and

an online gain adjusting unit that adjusts a control gain of the azimuth control unit, based on the yaw-angle-signal reference transfer function and the yaw-angular-velocity-signal reference transfer function set by the reference transfer function setting unit.

(Appendix 14) A vessel azimuth control method comprising:

a step in which an azimuth command generation unit generates an azimuth command signal indicating an azimuth to which a vessel should travel,

a step in which a yaw-angle detection unit outputs a yaw-angle signal indicating a rotation angle around a vertical axis passing through a gravity center of the vessel,

a step in which a yaw-angular-velocity detection unit outputs a yaw-angular-velocity signal indicating a rotation angular velocity around the vertical axis passing through the gravity center of the vessel,

a step in which a steering-angle detection unit outputs a steering-angle signal indicating an angle of a rudder of the vessel,

a step in which an azimuth control unit outputs a steering-angle command signal for making the vessel turn to the azimuth to which the vessel should travel, based on the azimuth command signal generated by the azimuth command generation unit, the yaw-angle signal outputted by the yaw-angle detection unit, and the yaw-angular-velocity signal outputted by the yaw-angular-velocity detection unit,
 a step in which a steering-angle control unit controls a rudder, based on the steering-angle command signal, and
 a step in which a calculation feasibility determination unit provided in a control gain adjustment unit determines feasibility of calculation of frequency responses, based on the steering-angle signal, the yaw-angle signal, and the yaw-angular-velocity signal, and in which, when the calculation feasibility determination unit determines that calculation of frequency responses is feasible, the control gain adjustment unit calculates respective frequency responses of the yaw-angle signal and the yaw-angular-velocity signal for the steering-angle signal and then adjusts a control gain of the azimuth control unit.

(Appendix 15) The vessel azimuth control method according to any one of claim 14, wherein the step in which the azimuth control unit outputs the steering-angle command signal includes

a step in which a first control calculation unit calculates a yaw-angular-velocity command signal for making a difference between the azimuth command signal and the yaw-angle signal become zero,
 a step in which a second control calculation unit calculates a feedback steering-angle command signal for making a difference between the yaw-angular-velocity command signal calculated by the first control calculation unit and the yaw-angular-velocity signal become zero,
 a step in which a third control calculation unit calculates a feed-forward steering-angle command signal, based on the yaw-angular-velocity command signal, and
 a step in which an adder adds the feedback steering-angle command signal calculated by the second control calculation unit and the feed-forward steering-angle command signal calculated by the third control calculation unit and then outputs a steering-angle command signal.

What is claimed is:

1. A vessel azimuth control apparatus comprising:
 an azimuth command generator that generates an azimuth command signal indicating an azimuth to which a vessel should travel;
 a yaw-angle detector that outputs a yaw-angle signal indicating a rotation angle around a vertical axis passing through a gravity center of the vessel;
 a yaw-angular-velocity detector that outputs a yaw-angular-velocity signal indicating a rotation angular velocity around the vertical axis passing through the gravity center of the vessel;
 a steering-angle detector that outputs a steering-angle signal indicating an angle of a rudder of the vessel;
 a vessel-speed detector that outputs a vessel-speed signal indicating a vessel speed of the vessel;
 an azimuth controller that outputs a steering-angle command signal for making the vessel turn to the azimuth to which the vessel should travel, based on the azimuth command signal generated by the azimuth command generator, the yaw-angle signal outputted by the yaw-

angle detector, and the yaw-angular-velocity signal outputted by the yaw-angular-velocity detector;
 a steering-angle controller that control a rudder, based on the steering-angle command signal outputted by the azimuth controller; and
 a control gain adjuster that has a calculation feasibility determinator for determining feasibility of calculation of frequency responses, based on the steering-angle signal, the yaw-angle signal and the yaw-angular-velocity signal, and that calculates respective frequency responses of the yaw-angle signal and the yaw-angular-velocity signal for the steering-angle signal outputted by the steering-angle detector, when the calculation feasibility determinator determines that calculation of frequency responses are feasible, and then adjusts a control gain of the azimuth controller.

2. The vessel azimuth control apparatus according to claim 1, wherein the calculation feasibility determinator of the control gain adjuster determines feasibility of calculation of the frequency responses, based on at least one of a degree of correlation among the steering-angle signal, the yaw-angle signal, and the yaw-angular-velocity signal, respective amplitudes thereof, respective changing amounts thereof, respective signal-to-noise ratios thereof, and respective fluctuation ratios thereof to disturbance.

3. The vessel azimuth control apparatus according to claim 2, wherein in accordance with the vessel-speed signal, the calculation feasibility determinator of the control gain adjuster changes a comparison threshold value for determining feasibility of calculation of the frequency responses, based on at least one of a degree of correlation among the steering-angle signal, the yaw-angle signal, and the yaw-angular-velocity signal, respective amplitudes thereof, respective changing amounts thereof, respective signal-to-noise ratios thereof, and respective fluctuation ratios thereof to disturbance.

4. The vessel azimuth control apparatus according to claim 1, wherein the calculation feasibility determinator of the control gain adjuster permits calculation of the frequency responses, when a changing amount of the steering-angle signal is larger than a predetermined changing amount.

5. The vessel azimuth control apparatus according to claim 1, wherein the control gain adjuster calculates a calculation accuracy, when respective frequency responses of the yaw-angle signal and the yaw-angular-velocity signal for the steering-angle signal are calculated, and adjusts a control gain of the azimuth controller, based on the frequency responses calculated at a time when the calculation accuracy is higher than a predetermined accuracy.

6. The vessel azimuth control apparatus according to claim 5, wherein the control gain adjuster learns the frequency responses calculated at a time when the calculation accuracy is higher than a predetermined accuracy.

7. The vessel azimuth control apparatus according to claim 6, wherein the control gain adjuster applies weighting corresponding to the calculation accuracy to the calculated frequency responses and then learns the weighted frequency responses.

8. The vessel azimuth control apparatus according to claim 1, wherein the control gain adjuster calculates a steering-angle offset amount that is a counter-steering amount at a time of straight sailing and then adjusts a control gain of the azimuth controller.

9. The vessel azimuth control apparatus according to claim 8, wherein the control gain adjuster calculates the

25

steering-angle offset amount by a difference equation, based on a model where the steering-angle offset amount is explicitly expressed.

10. The vessel azimuth control apparatus according to claim 8, wherein the steering-angle controller that controls a rudder, based on the steering-angle command signal and the steering-angle offset amount.

11. The vessel azimuth control apparatus according to claim 8, wherein the calculation feasibility determinator of the control gain adjuster determines feasibility of calculation of the frequency responses, based on the steering-angle signal and the steering-angle offset amount.

12. The vessel azimuth control apparatus according to claim 1, wherein the azimuth controller includes

a first control calculator that calculates a yaw-angular-velocity command signal for making a difference between the azimuth command signal and the yaw-angle signal become zero,

a second control calculator that calculates a feedback steering-angle command signal for making a difference between the yaw-angular-velocity command signal calculated by the first control calculator and the yaw-angular-velocity signal become zero,

a third control calculator that calculates a feed-forward steering-angle command signal, based on the yaw-angular-velocity command signal, and

an adder that adds the feedback steering-angle command signal calculated by the second control calculator and the feed-forward steering-angle command signal calculated by the third control calculator and then outputs a steering-angle command signal.

13. The vessel azimuth control apparatus according to claim 1, wherein the control gain adjuster includes

a reference transfer function setter that sets a yaw-angle-signal reference transfer function having target frequency responses for the yaw-angle signal and a yaw-angular-velocity-signal reference transfer function having target frequency responses for the yaw-angular-velocity signal, with regard to the steering-angle signal, and

an online gain adjuster that adjusts a control gain of the azimuth controller, based on the yaw-angle-signal reference transfer function and the yaw-angular-velocity-signal reference transfer function set by the reference transfer function setter.

26

14. A vessel azimuth control method comprising: generating an azimuth command signal indicating an azimuth to which a vessel should travel, outputting a yaw-angle signal indicating a rotation angle around a vertical axis passing through a gravity center of the vessel, outputting a yaw-angular-velocity signal indicating a rotation angular velocity around the vertical axis passing through the gravity center of the vessel, outputting a steering-angle signal indicating an angle of a rudder of the vessel, outputting a steering-angle command signal for making the vessel turn to the azimuth to which the vessel should travel, based on the azimuth command signal generated by the azimuth command generator, the yaw-angle signal outputted by the yaw-angle detector, and the yaw-angular-velocity signal outputted by the yaw-angular-velocity detector, controlling a rudder, based on the steering-angle command signal, and determining feasibility of calculation of frequency responses, based on the steering-angle signal, the yaw-angle signal, and the yaw-angular-velocity signal, and in which, when the calculation feasibility determinator determines that calculation of frequency responses are feasible, calculating respective frequency responses of the yaw-angle signal and the yaw-angular-velocity signal for the steering-angle signal and then adjusting a control gain of the azimuth controller.

15. The vessel azimuth control method according to claim 14, wherein outputting the steering-angle command signal includes

calculating a yaw-angular-velocity command signal for making a difference between the azimuth command signal and the yaw-angle signal become zero,

calculating a feedback steering-angle command signal for making a difference between the yaw-angular-velocity command signal calculated by the first control calculator and the yaw-angular-velocity signal become zero, calculating a feed-forward steering-angle command signal, based on the yaw-angular-velocity command signal, and

adding the feedback steering-angle command signal calculated by the second control calculator and the feed-forward steering-angle command signal calculated by the third control calculator and then outputting a steering-angle command signal.
